Primary Examiner — Brian N Vinson(74) *Attorney, Agent, or Firm* — King & Spalding LLP(57) **CLAIM**

The ornamental design for a light fixture cover, as shown and described.

DESCRIPTION

FIG. 1 is a top-side-front perspective view of a light fixture cover, showing our new design;

FIG. 2 is a bottom-side-front perspective view of the light fixture cover of FIG. 1;

FIG. 3 is a front elevation view of the light fixture cover of FIG. 1;

FIG. 4 is a rear elevation view of the light fixture cover of FIG. 1;

FIG. 5 is a right-side elevation view of the light fixture cover of FIG. 1;

FIG. 6 is a left-side elevation view of the light fixture cover of FIG. 1;

FIG. 7 is a top plan view of the light fixture cover of FIG. 1; and,

FIG. 8 is a bottom plan view of the light fixture cover of FIG. 1.

The broken line disclosure represents portions of the light fixture cover which forms no part of the claimed design.
